(57) **CLAIM**

The ornamental design for a wood-type head for a golf club, substantially as shown.

DESCRIPTION

FIG. 1 is a perspective view showing the front, top and toe sides of a wood-type head for a golf club embodying the new design;

FIG. 2 is a front elevation view thereof;

FIG. 3 is a toe side elevation view thereof;

FIG. 4 is a heel side elevation view thereof;

FIG. 5 is a rear elevation view thereof;

FIG. 6 is a top plan view thereof;

FIG. 7 is a bottom plan view thereof;

FIG. 8 is an enlarged fragmented sectional view taken generally on the line 8—8 of FIG. 2;

FIG. 9 is a front elevation view showing a golf club head embodying one alternative form of the new design, the top, bottom, toe, heel and rear sides of the golf club head being identical to the embodiment of FIGS. 1-7;

FIG. 10 is a front elevation view showing a golf club head embodying another alternative form of the new design, the top, bottom, toe, heel and rear sides of the golf club head being identical to the embodiment of FIGS. 1-7; and,

FIG. 11 is an enlarged fragmented sectional view taken generally on the line 11—11 of FIG. 10.
